DESIGN FOR AN APPLIQUE EMBLEM OR SIMILAR ARTICLE FOR WEARING AP- PAREL

Charles Emmey, New York, N. Y.

Application February 13, 1936, Serial No. 61,134

Term of patent 3½ years

To all whom it may concern:

Be it known that I, Charles Emmey, a citizen of the United States, residing in the city and county of New York, State of New York, have invented a new, original, and ornamental Design for an Applique Emblem or Similar Article for Wearing Apparel, of which the following is a specification, reference being had to the accompanying drawing, forming part thereof.

The figure is a plan view of an applique emblem for wearing apparel, showing my design. Said emblem is of no appreciable thickness.

I claim:

The ornamental design for an applique emblem or similar article for wearing apparel, substantially as shown and described.

CHARLES EMMEY.
